UNITED STATES PATENT OFFICE

JOE J. ETTINGER, OF WARSAW, INDIANA, ASSIGNOR TO ZIMMER MANUFACTURING COMPANY, OF WARSAW, INDIANA, A CORPORATION

CLAVICLE SPLINT

Application filed August 12, 1932. Serial No. 628,610.

This invention relates to surgical appliances and has special reference to a clavicle splint such as is used in the treatment of fractures of the human clavicle.

More particularly the invention relates to improvements in the clavicle splint for which application for patent was filed by me on September 19, 1931, Ser. No. 563,846, and which has since eventuated as Patent No. 1,880,946, dated October 4, 1932.

One important object of the invention is to provide improved means for connecting the shoulder plates across the front of the chest in such a device.

A second important object of the invention is to provide an improved form of shoulder plates or shields in such a device.

A third important object of the invention is to provide a novel construction of such a splint wherein provision is made whereby certain of the securing straps may be connected to the shields at any one of a series of points selectively.

A fourth important object of the invention is to provide novel means for connecting the strap ends and shields or shoulder plates.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a front view of the splint complete.

Figure 2 is an enlarged detail section on the line 2-2 of Figure 1.

Figure 3 is a front elevation of the parts shown in Figure 2.

Figure 4 is an enlarged detail section on the line 4-4 of Figure 1.

Figure 5 is an enlarged section of a shield or shoulder plate on the line 5-5 of Figure 1.

Figure 6 is a similar view on the line 6-6 of Figure 1.

Figure 7 is an enlarged elevation of one of

the shields, the view being taken from the inner edge thereof, the holes in the plate being omitted.

Figure 8 is a detail view showing a strap securing member used herewith.

In the construction herein disclosed there is provided a pair of shoulder plates or shields 10. These shields, when viewed from in front, present a roughly lunate appearance, the ends or cusps of the lune being rounded off. Thus each shield has a concave outer edge 11 and a convex inner edge 12 joined at their ends by arcuate edges 13 which flare smoothly into the edges 11 and 12. With the exception of a lip portion 14 on the outer edge near the upper end, the posterior surface of each shield is of general concave shape. At the lower end the concavity is very slight, as may be seen from Fig. 4, and this part lies in front of the upper anterior portion of the chest. Above this end the concavity is deeper as shown in Figs. 2, 5 and 6, and at the same time there is a general spiral twisting of the plate from which the shield is formed so that the inner edge, which lies at its lower end more forwardly than the outer edge, is extended back over the shoulder to lie at its upper end above and to the rear of the outer edge. This brings the upper cusp portion, which is concave in all directions on top of the front portion of the shoulder joint so that, when secured by the straps and tie bars, as will presently be described, the shoulder joint is supported firmly against forward movement. When in use, the forwardly turned lip is positioned in front of the axilla so that a certain amount of forward movement is permitted the upper arm while the socket of the shoulder joint is immobilized as above noted. The posterior surfaces of the shields are provided with the usual pads or cushions 15 of felt or other suitable material.

Somewhat below and inwardly from the middle of each shield is a pivot stud 16 whereon is mounted a hinge plate 17 having a hinge barrel 18 at its inner end and provided with an arcuate slot 19 concentric to the stud 16 and adjacent its outer end. A stud bolt 20 and

is carried by the shield 10 and extends through the slot 19, being provided on its forward end with a butterfly nut 21. By this means the shield is permitted to swing 5 slightly on the pivot 16 and, when adjusted to desired position, is there held by tightening the nut 21. A pintle 22 is held in each barrel 18 and carries the arms of the forked end 23 of a chest bar or tie bar 24 arcuate 10 in plan to conform to and lie in closely spaced relation from the chest of the patient. The two chest bars are arranged one in front of the other and each is provided with a longitudinal slot 25. A clamp bolt 26 is carried 15 by the free end of each bar and extends through the slot of the other bar, being provided on its threaded end with a butterfly nut 27. With the nuts 27 loose, the bars may be slid, one on the other, to adjust the 20 distance between the shields and when adjusted the nuts may be tightened to hold the parts in desired position. The hinges serve to permit the shields to conform to the flatness or rotundity of the patient's chest. 25 In order to hold the lower ends of the shields pressed firmly against the chest there is provided a back strap consisting of two sections 28 which are adjustably connected at their inner ends by a buckle 29 of any preferred type. The free end of each of the 30 sections 28 carries a loop 30 from which projects a tongue 31 having a terminal portion 32 offset rearwardly of the portion adjacent the loop. In the lower part of each shield 35 is a series of laterally spaced rows of vertically spaced holes 33 adapted to receive the respective tongue which is inserted through the selected hole 33 from the front so that the offset portion 32 lies against the posterior 40 surface of the shield as well shown in Fig. 4. By this means the back strap may be connected to the shields at such points as will prevent the strap sections from cutting into the axillæ while ensuing that the connection 45 is high enough to prevent the shields from moving upwardly out of proper positions. Moreover, the spacing of the rows permits of additional adjustment of the strap for length and of putting a pulling stress 50 on the shields at such points in their widths as to obtain the best effect in the particular case under treatment.

Diagonal cross or shoulder straps 34 each have one end suitably fixed, as by sewing, to 55 a respective strap section 28 near one of the shields and extend diagonally across the patient's back to the upper part of the remaining shield where it is secured by a buckle 35 fixed to the upper rear end of that shield. 60 These straps serve to pull the upper parts of the shields rearwardly and to hold them down on the points of the shoulders.

By reason of the novel arrangement of the 65 arcuate tie bars outer clothing may be worn over the splint without inconvenience. Also

the peculiar shape of the splint with its spiral twist and cupped upper part, together with the novel strap arrangement, enables rearward abduction to be exerted on the shoulder joint in such manner as to hold the segments of a fractured clavicle properly aligned with slight discomfort to the patient and no unnecessary immobilization of the upper arm.

There has thus been provided a simple 75 and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

1. In a clavicle splint, a pair of rigid plates shaped to conform to the front and shoulder joint part of the shoulder region of a human body, a back strap, coacting means on the ends of said strap and the lower parts of said plates for connecting said ends to a selected point of a multiplicity of connection points on said lower parts, buckles each fixed to the upper end of a respective plate, a pair of shoulder straps arranged in crossed relation and each having one end secured to the back strap adjacent a respective plate and having its other end secured to the buckle of the other plate, hinge plates each pivotally mounted on the front face of one of said rigid plates, means to secure the hinged plates in adjusted pivotal positions on said rigid plates, and rigid connecting means having its ends hinged respectively to the hinge plates.

2. In a clavicle splint, a pair of rigid plates shaped to conform to the front and shoulder joint part of the shoulder region of a human body, a back strap, coacting means on the ends of said strap and the lower parts of said plates for connecting said ends to a selected point of a multiplicity of connection points on said lower parts, buckles each fixed to the upper end of a respective plate, a pair of shoulder straps arranged in crossed relation and each having one end secured to the back strap adjacent a respective plate and having its other end secured to the buckle of the other plate, hinge plates each pivotally mounted on the front face of one of said rigid plates to swing about an axis normal to the plate, means to secure the hinged plates in adjusted pivotal positions on said rigid plates, rigid connecting means having its ends hinged respectively to the hinge plates, the axes of the hinge connections being substantially at right angles to the pivotal axes of the respective hinge plate, said rigid connecting means including a pair of

bars slidably overlapping each other at their ends and each having its outer end hinged to a respective hinge plate, said bars being flatly arched to conform to and lie in closely spaced relation to a human chest, and clamp bolts securing said bars in slidably adjusted position.

3. In a clavicle splint, a pair of rigid plates shaped to conform to the front and shoulder joint part of the shoulder region of the human body, a back strap, coacting means on the ends of said strap and the lower parts of said plates for connecting said ends to a selected point of a multiplicity of connection points on said lower parts, the connection points for the plates consisting of horizontally spaced rows of vertically spaced connection elements, buckles each fixed to the upper end of a respective plate, a pair of shoulder straps arranged in crossed relation and each having one end secured to the back strap adjacent a respective plate and having its other end secured to the buckle of the other plate, hinge plates each pivotally mounted on the front face of one of said rigid plates to swing about an axis normal to the plate, means to secure the hinged plates in adjusted pivotal positions on said rigid plates, and rigid connecting means having its ends hinged respectively to the hinge plates, the axes of the hinge connections being substantially at right angles to the pivotal axes of the respective hinge plates, said rigid connecting means being adjustable for length and being provided with means for holding it in length adjusted position.

4. In a clavicle splint, a pair of rigid plates each bluntly lunate in form and having a concave outer edge, a convex inner edge and rounded ends, the posterior surfaces of said plates being generally convex and the upper part of each plate being spirally twisted with

respect to the lower part thereof whereby the upper part of the plate may lie on top of a shoulder joint of a human body upon the lower part of the plate being positioned to press against the lateral chest portion of such body below said joint, a back strap, coacting means on the ends of said strap and a plurality of connection points on the lower parts of said plates for connecting said ends to selected pairs of said connection points, a pair of shoulder straps connecting said back strap and the upper parts of the plates, hinge plates each pivoted to a respective plate to swing about an axis normal to said plates, means to hold said hinge plates in adjusted position, a flatly arched bar having its ends hinged to said hinge plates to swing on axes parallel to said plates, means to permit said bar to be adjusted for length, and means to hold the bar in length adjusted position.

5. In a clavicle splint, a pair of shoulder plates for engaging the shoulders of a patient, hinge plates each mounted pivotally on a respective shoulder plate to swing about an axis normal to the plate, means to hold said hinge plates in pivotally adjusted position, and rigid connecting means pivoted to said hinge plates at its ends.

6. In a clavicle splint, a pair of shoulder plates for engaging the shoulders of a patient, hinge plates each mounted pivotally on a respective shoulder plate to swing about an axis normal to the plate, means to hold said hinge plates in pivotally adjusted position, rigid extensible connecting means pivoted to said hinge plates at its ends, said connecting means being flatly arched throughout its length, and means to hold the connecting means in adjusted extension.

In testimony whereof I affix my signature.
JOE J. ETTINGER.
